UNITED STATES PATENT OFFICE.

ROBERT F. WHITNEY, OF WINCHESTER, MASSACHUSETTS, ASSIGNOR OF ONE-HALF TO
ARTHUR E. WHITNEY, OF WINCHESTER, MASSACHUSETTS.

HIDE-WORKING MACHINE.

No. 900,834.

Specification of Letters Patent.

Patented Oct. 6, 1908.

Application filed January 4, 1907. Serial No. 350,793.

To all whom it may concern:

Be it known that I, ROBERT F. WHITNEY, a citizen of the United States, and resident of Winchester, in the county of Middlesex 5 and State of Massachusetts, have invented certain new and useful Improvements in Hide-Working Machines, of which the following is a specification.

This invention relates to machines for fleshing, unhairing and working hides and its object is to secure a machine having a smooth and positive action and with its rolls so arranged as to secure a wide opening for feeding the hide.

15 The invention is illustrated by the accompanying drawings in which—

Figure 1 is an elevation of the left end of the machine in operative position. Fig. 2 is an elevation of the right end of the machine in inoperative position. Fig. 3 is a top plan view of the machine in operative position, with portions of the rolls cut away. Fig. 4 is a diagram of certain parts in operative position. Fig. 5 is a diagram of the 25 same parts in inoperative position.

Similar characters refer to similar parts throughout the several drawings.

The main frame of the machine consists of the side frames 1 connected by the ties 2. 30 The work roll 3 is mounted on the shaft 4 journaled in suitable bearings 5 in the frame and provided with operating blades 6. The bed roll 7 is mounted on the shaft 8 journaled in suitable bearings in the free ends 9 of the 35 swinging arms 10 rotatably mounted on the studs 11 fixed to the frame. The front feed roll 12, which I call the "pinch roll," is mounted on the shaft 13, which is suitably journaled in movable boxes 14 and also in 40 the swinging arms 19. These boxes 14 are provided with the rods 15 and 15^a, controlled by the springs 18, adjustably arranged and adapted to slide back and forth in swinging frames 16 rotatably mounted on the studs 45 17 fixed to the frame 1. The swinging arms 19 are pivoted at 20 to the swinging arms 10. The back feed roll 22, which I call the "feed roll," is mounted upon the shaft 23 journaled in suitable bearings 24 in the swinging arms 50 25 rotatably pivoted at 26 to the swinging arms 27 rotatably mounted on the studs 28 fixed to the frame. The threaded rods 29 are pivoted at 30 to the swinging arms 25 and extend through the upper end of the swinging arms 27 in sliding contact therewith and

on said rods are adjustably mounted the controlling springs 31. These two feed rolls, or pinch and feed roll, 12 and 22, are mechanically connected by the links 32 pivoted at 33 to the swinging arms 27 and at 34 to the 60 swinging frames 16.

The swinging arms 10 are moved about their axes (studs 11) by the toggles (toggle-joints 35) comprising the links 36 pivoted to said swinging arms at 37 and the links 38 pivoted at 39 to the rocker arms 40, said rocker arms being pivoted at 41 to the frame. The rods 42 are pivoted at 43 to the rocker arms 40 and extend downwardly through the lugs 44 on the frame and upon their lower 70 ends are screwed the nuts 45 which engage said lugs and limit the upward movement of said rods and are held in place by the check nuts 46. These rods are furnished with adjustable nuts 47 between which and lugs 44 75 are adjustably arranged the springs 48 adapted to be compressed by the downward movement of said rods and to react to raise them. The arrangement of the springs 18 and 31 is similar to that just described. 80

The shafts 49, hereinafter more fully described, have fixed to their outer end the short arms 50 which encircle the rods 42 between and engaging the lugs 44 and the nuts 45. Rigidly fixed to the shaft 49 are the 85 treadles 51 by depressing which the operator lowers said rods 42. The downward movement of the treadles 51 is limited by the set screws 52 in the ears 53 of the arms 50 arranged to contact with the lugs 44. The 90 longitudinally adjustable crank rods 54 are pivoted at their upper end to the toggle-joints 35 and at their lower end to the crank pins 55 carried by the cranks 56 and 56^a fixed to the rotary crank shaft 57 mounted in the 95 frame, the crank 56 having a gear 58. From the left of the frame is projected a bracket 59 in which is mounted the rotary shaft 61. The fixed stud 62 is also projected from the frame. 100

The operating mechanism comprises the following gears and pulleys: The work roll shaft 4 has fixed to its right end the pulley 64 driven by the belt 65 and is driven by said pulley independently of all the other mechanism of the machine; the pulley 66 is fixed to the shaft 61 and is driven by the belt 67; the pinch roll 12 has fixed to its right end the gear 68; the feed roll 22 has fixed to its right end the gear 69 which has a wide face to en- 110

gage the two gears 68 and 71; the bed roll 7 has fixed to its right end the gear 71 and to its left end the gear 72; on the shaft 61 are fixed the sprocket 73 and the gear 74; the 5 sprocket 73 is connected by the chain 75 with the sprocket 76 which is rotatably mounted on the stud 62 and carries the driving member 76^a of a clutch, the driven member of which clutch is arranged loosely on said stud 10 62 and carries the gear 77 adapted to engage the gear 58 of the crank 56. This clutch may be of any description with suitable means for throwing the clutch members into and out of engagement. The drawings (Fig. 1) show a 15 15 clutch operated by a weighted lever 79 pivoted at 80 to the frame and raised by depressing the treadle 81 which is loosely mounted on the crank shaft 57 and connected to said lever 79 by the chain 82 which passes 20 over guide pulleys 83 mounted in the frame; but any form of clutch or any other means may be used to rotate the crank 56.

The clutch is not described fully as it forms no part of this invention but it indicates a clutch for which I have filed an application for Letters Patent of the United States so constructed and arranged that when the operator depresses the treadle 81 the driven member of the clutch engages the 30 driving member rotating the crank shaft 57 as described. If the operator's foot is removed from the treadle, the weighted lever 79 automatically disengages the clutch when the crank is in the positions shown in Fig. 1 35 and Fig. 2, the operating rolls remaining together, or separated, until the operator again depresses the treadle. The crank shaft gear 58 makes one half a revolution to one revolution of the clutch gear 77.

40 The shafts 49 have their outer end journaled in the frame 1 and their inner end journaled in the common bearing 84 fixed to the floor, or otherwise suitably mounted, and may be each independently operated by the 45 relief treadles 51 fixed to said shafts.

The rolls are spring-controlled as shown to enable them to meet and adapt themselves to the inequalities of the hide, a provision common in these machines. But in addition 50 to this usual provision I have provided the additional relief treadles, which enable the operator to move either end of said bed roll from said work roll by depressing one or the other of said treadles as may be desired. 55 This double relief treadle is simply a modification of the single relief treadle shown and described in the patent to me dated August 28, 1906, No. 829,613.

The operation of the machine is as follows: 60 The belts are set in motion and rotate the work roll shaft 4; sprocket 73 and gear 74 on shaft 61; and sprocket 76 on shaft 63. The operator adjusts the hide (Fig. 5) and depresses treadle 81 thereby engaging the 65 clutch members, rotating crank 56 and bring-

ing bed roll, feed roll and pinch roll into operative position (Fig. 4); gear 72 into engagement with gear 74; gear 71 into engagement with gear 69; and gear 68 into engagement with gear 69; rotating the several rolls 70 in the direction indicated by the arrows (Fig. 4); and the hide is carried between the rolls and operated upon by the work roll. When the rolls come into engagement, the operator disengages the clutch, or preferably the 75 clutch is disengaged automatically by any suitable means, as by the arrangement indicated. When the hide has been operated upon, the operator again engages the clutch members by depressing the treadle thus 80 rotating the crank and carrying the rolls into the original inoperative position shown in Fig. 5.

From Fig. 4 it will be seen that in the operative position the following parts are in 85 alinement: crank shaft 57, crank pin 55 and toggle joint 35; stud 11, pivot 20 and shaft 13; shaft 23, shaft 13 and stud 17; shaft 23, stud 28 and pivot 34; pivot 34, pivot 33 and stud 17; pivot 37, toggle joint 35 and pivot 90 39; stud 11, pivot 37, shaft 8, shaft 23, stud 28 and pivot 34. By this arrangement of the parts the normal pressure exerted by the hide as it is being fed and the extra pressure caused by inequalities in the hide are 95 exerted almost entirely along the lines joining the shafts of the several swinging rolls with their respective fulcra or studs 11, 17 and 28, and when these rolls are locked in operative position by means of the toggles and 100 cranks, as shown and described, the pressures are all in the direction of one or more of the alinement pointed out above and as a result the action of the machine is more positive, smoother and stronger than in any 105 prior machines. By swinging the several rolls as shown and described, namely, the pinch roll and the bed roll downwardly and forwardly (toward the front of the machine) and the feed roll upwardly and backwardly, 110 a large opening is obtained for inserting the hide. Another advantage of this arrangement is that the feed roll helps to counter-balance the weight of the pinch roll and bed roll.

115 The drawings show the rolls with their shafts journaled in bearings mounted in swinging arms but such shafts may be journaled in bearings mounted in guide-ways and movable therein by swinging arms 120 or their equivalents; and I claim broadly the combination of rolls whose shafts are journaled in movable boxes with means for moving such boxes in certain directions, thereby bringing such rolls together or 125 separating them.

Having described my invention what I claim and desire to secure by Letters Patent is:

1. A hide working machine comprising the 130

- frame 1 and mounted thereon the work roll 3, bed roll 7 mounted in swinging arms 10 pivoted to said frame, pinch roll 12 mounted in swinging frames 16 pivoted to said frame 5 1 and in swinging arms 19 pivoted to said swinging arms 10, and feed roll 22 mounted in swinging arms 25 pivoted to swinging arms 27 pivoted to said frame 1 and connected by links 32 with said swinging frames 16, with 10 means for rotating the swinging arms of the bed roll about their axes and thereby bringing the rolls into and out of operative position; substantially as described.
2. A hide working machine comprising the frame 1 and mounted thereon the work roll 3, bed roll 7 mounted in swinging arms 10 pivoted to said frame, pinch roll 12 mounted in swinging frames 16 pivoted to said frame 1 and in swinging arms 19 pivoted to said 15 swinging arms 10, and feed roll 22 mounted in swinging arms 25 pivoted to swinging arms 27 pivoted to said frame 1 and connected by links 32 with said swinging frames 16, one or more of said rolls being spring controlled, 20 such controlling springs, with means for rotating the swinging arms of the bed roll about their axes and thereby bringing the rolls into and out of operative position; substantially as described.
3. A hide working machine comprising a frame and mounted thereon a work roll, a bed roll mounted in swinging arms pivoted to said frame, a pinch roll mounted in swinging arms pivoted to the swinging arms of the 25 bed roll and a feed roll mounted in swinging arms pivoted to the frame and connected by links with the swinging arms of the pinch roll, with means for rotating the swinging arms of the bed roll about their axes and 30 thereby bringing the rolls into and out of operative position; substantially as described.
4. A hide working machine comprising a frame and mounted thereon a work roll, a bed roll mounted in swinging arms pivoted to said frame, a pinch roll mounted in swinging arms pivoted to the swinging arms of the bed roll and a feed roll mounted in swinging arms pivoted to the frame and connected by 35 links with the swinging arms of the pinch roll, one or more of said rolls being spring controlled, such controlling springs, with means for moving the swinging arms of the bed roll about their axes and thereby bringing the rolls into and out of operative position; substantially as described.
5. A hide working machine comprising a frame and mounted thereon a work roll, a bed roll mounted in bearings mov-
- able to and away from the work roll, a feed roll mounted thereon in bearings movable to 60 and away from said bed roll and a pinch roll mounted thereon in bearings movable to and away from said feed roll with means for moving said bed roll to and away from said work roll thereby through intermediate mechanism 65 bringing the rolls into and out of operative position, together with such intermediate mechanism; substantially as described.
6. A hide working machine comprising a frame and mounted thereon a work roll, a bed roll mounted thereon in bearings movable to and away from the work roll, a feed roll mounted thereon in bearings movable to 70 and away from said bed roll and a pinch roll mounted thereon in bearings movable to and away from said feed roll, one or more of said rolls being spring-controlled, such controlling springs, with means for moving said bed roll to and away from said work roll thereby through intermediate mechanism bringing 75 the rolls into and out of operative position, together with such intermediate mechanism; substantially as described.
7. A hide working machine comprising a frame and mounted thereon a work roll, a bed roll mounted in swinging arms pivoted to said frame, one or more feed rolls mounted thereon, one of said feed rolls being mounted in swinging arms pivoted to the swinging arms of the bed roll, with means for rotating 80 the swinging arms of the bed roll about their axes and thereby through intermediate mechanism bringing the rolls into and out of operative position, together with such intermediate mechanism; substantially as described.
8. A hide working machine comprising a frame and mounted thereon a work roll, a bed roll mounted in swinging arms pivoted to said frame, one or more feed rolls mounted thereon, one of said feed rolls being mounted in swinging arms pivoted to the swinging arms of the bed roll, one or more of said rolls being spring-controlled, such controlling springs, with means for rotating the swinging arms of the bed roll about their axes and 85 thereby through intermediate mechanism bringing the rolls into and out of operative position, together with such intermediate mechanism; substantially as described.
9. A hide working machine comprising a frame and mounted thereon a work roll, a bed roll mounted in swinging arms pivoted to said frame, one or more feed rolls mounted thereon, one of said feed rolls being mounted in swinging arms pivoted to the swinging arms of the bed roll, one or more of said rolls being spring-controlled, such controlling springs, with means for rotating the swinging arms of the bed roll about their axes and 90 thereby through intermediate mechanism bringing the rolls into and out of operative position, together with such intermediate mechanism; substantially as described.
10. A hide working machine comprising a frame and mounted thereon a work roll, a bed roll mounted in bearings movable to and away from the work roll, a feed roll mounted thereon in bearings movable to and away from said bed roll and a pinch roll mounted thereon in bearings movable to and away from said feed roll with means for moving said bed roll to and away from said work roll thereby through intermediate mechanism bringing the rolls into and out of operative position, together with such intermediate mechanism; substantially as described.

In testimony whereof I have affixed my signature, in presence of two witnesses.

ROBERT F. WHITNEY.
